JOSEPH W. THORN, OF COURTLAND, ALABAMA.

Assign to himself and Charles W. Matthews.
Letters Patent No. 74,716, dated February 25, 1868.

IMPROVEMENT IN COTTON-CLEANER.

The Schedule referred to in these Letters Patent and making part of the same.

TO ALL WHOM IT MAY CONCERN:

Be it known that I, JOSEPH W. THORN, of the city of Courtland, county of Lawrence, in the State of Alabama, have invented a new and useful Improvement in "Cotton-Cleaners;" and I hereby declare that the following is a full, clear, and exact description of my invention, reference being had to the accompanying drawings making a part of this specification, in which—

Figure 1, plate 1, is a side elevation of my cotton-cleaning machine.

Figure 1, plate 2, a plan view of the machine.

Figure 2, plate 2, a longitudinal sectional elevation of the machine.

Similar letters of reference apply to similar parts of the machine.

The object of my improvement is to provide a machine for cleaning cotton, with a revolving feeding-drum, of a simple construction and operation, by the application of which machines for cotton-cleaning may be cheaply and easily fed.

To enable others skilled in the art to make and use my invention, I will proceed to describe its construction and operation.

F is the wooden or metallic framework of the machine; B B, the fans or cylindrical beaters, made in the usual way a lengthy, description of which I do not deem necessary to give, as my invention does not bear principally on them. M M is the cleaning-box, with the usual wire arrangement around it. F A is the drum of my feeding-apparatus, its hollow cylinder mounted on an axle, A B, and divided inside by partitions, six, or less or more, in number, resting on the axle, and within the exterior envelope E E. Said feeding-drum or cylinder, thus prepared, is set on the machine on the uprights V P, and protected, outside, by exterior envelope E E, and should be placed so as to fill up the top opening space O P of cleaning-box M. On one end of shaft A B is set a circular ratchet, C R, and lever-catch C T. Catch C T is set firmly on lever L, which hangs on axle A B, as a fulcrum, for the purpose hereinafter shown. The opening between the lower part of cleaning-box M and envelope E E of the drum is shut up or open at will, by door D. Said door is held in proper place by and fastened tight to axle X, which, in its rotary alternate movement, as hereinafter shown, opens and closes door D. On one end of axle X, on the same side of the machine with ratchet C R, is set a small lever, L', which is held in proper position by catch C K, and which will, when catch C K is removed, fall in position P S, shown in red lines in the drawings, fig. 2, plate 2. This movement of lever L' is made sure by the alternate falling and rising of a rod and weight, W, set for the purpose, at the opposite end of shaft X.

The machine is set in motion by means of pulleys P L and P' L', and gearing a b c d e. Belt B on pulley a b drives wheel a, which, by means of pinion p, drives wheel c, which, by means of pinion p', drives cog-wheel d. On the inside face of said wheel d are projected circular lugs l g l' g' l'' g''; l' g' being nearer the centre of the wheel than the two others. In the rotary movement of wheel d, lug l'' g'', passing above catch-lever L'', knocks against catch C K, thus allowing lever L', with weight W, to fall to the position P S, shown in red, plate 1, driving open door D. Next comes lug l' g'', which, passing under catch-lever L', catches lever L', and pushes it up, as well as weight W, until catch C K has been thus permitted to hold L' in its former position, and door D is closed again. Meanwhile lug l g travels up, pushes lever L up, said movement acting on ratchet C K, so as to drive drum F A, as shown per arrow in red ink, and when it (lever L) escapes lug l g, lever L falls of its own weight into its former position, catch C T thus catching on the next notch or tooth of the ratchet. The relative positions of lug l g l' g' l'' g'' are so calculated that, through the medium of the parts acting in connection therewith, drum F A will throw a new supply of cotton to the cleaning-place M only when a supply of clean cotton has been ejected through door D, and said door closed up again by the described movement of lug l' g', on lever L'.

I have not thought necessary to describe any of the parts of the machine which I do not intend to claim as new. Nor do I intend to claim broadly, in this specification, the whole of the machine herein described, said machine having been mainly described and claimed in my patent, dated sixteenth day of October, eighteen hundred and sixty.

I have simplified considerably the first machine I invented, on cotton-cleaning, by rendering the feeding-apparatus self-acting, and considerably simplifying the gearing. My above-described invention and improve-

ment give all the facility and cheapness as well as perfection of work that can be desired in a contrivance of that kind. One single belt, connected with any power, steam or otherwise, sets the whole in motion, and the cotton thrown in the machine in its dirty, crude state, comes out neat and clean.

Having thus described my invention, what I claim, and desire to secure by Letters Patent of the United States, is—

1. Feeding-drum F A, catch-lever L, C T, ratchet C R, and lug l g, the whole combined and constructed and operating in the manner and for the purpose above set forth and described.

2. Lever L', catch C K, door D, and weight W, the whole combined in the manner and for the purpose above set forth and described.

3. The combination of drum F A, its catch-lever L C T, and ratchet C R, and door D, lever L', and catch C K, and weight W, with a cotton-beating and cleaning-machine, the whole constructed and operated in the manner and for the purpose above set forth and described.

J. W. THORN.
